FRANK L. DODGSON, OF ROCHESTER, NEW YORK, ASSIGNOR TO GENERAL RAILWAY SIGNAL COMPANY, OF ROCHESTER, NEW YORK

RAILWAY-TRAFFIC-CONTROLLING SYSTEM

Application filed October 3, 1928. Serial No. 310,094.

This invention relates to a system for controlling a distant switch machine of a railway system, together with means for indicating the operation of such switch machine and the passage of a train by the switch operated by such switch machine.

In accordance with the present invention it is proposed to employ a single circuit connecting a local dispatcher's office and a switch machine at a distant point over which circuit the switch machine may be controlled and distinctive indications received giving information as to the operation of the switch machine and the passage of a train by such distant point. More specifically, it is proposed to give a non-flashing continuing indication so long as detector track circuit associated with the track switch operated by such switch machine is occupied, and to give a blinking flashing continuing indication if the switch machine, for some reason or other, does not complete its operating stroke, possibly because suitable overload circuit controlling means has been operated.

Other objects, purposes, and characteristic features of the present invention will in part be apparent from the accompanying drawings and will in part be described hereinafter.

In describing the invention in detail reference will be made to the accompanying single drawing illustrating conventionally one embodiment of the invention.

Referring to the drawing the main track rails have been designated 3 and the rails of the passing siding have been designated 4, these rails being insulated at points to define the usual detector track circuit associated with the track switch 6 joining the siding with the main track by insulating joints 5, this detector track circuit including the track battery 7 and the detector track relay DT.

In the conventional track layout illustrated trains passing over the track switch 6 are protected and governed by starting signals 2 and 2^d, an entering signal 1 and a take-siding signal 1^d, these signals being governed in any suitable manner in accordance with traffic conditions in advance thereof, the position of the track switch and the energized condition of the control relay Z, or in a man-

ner as more specifically described in the prior application of S. N. Wight, Ser. No. 120,423, filed July 3, 1926, or may be governed only in accordance with traffic conditions and the position of the track switch.

The switch 6 is power operated by a suitable switch machine of either the electro-pneumatic or all-electric type as conventionally shown by the dotted rectangle SM designating an all-electric type switch machine, and the position of this switch is manifested by the contacts in the switch box SB. In the particular arrangement shown the switch machine is controlled by a control relay Z, the flashing relay FL, the stick relay NS or RS, and the thermal relay NTR or RTR which latter relays are employed to protect the switch machine against excessive or prolonged current consumption, and further this arrangement shows means for giving an indication in the tower when such current flow has been interrupted by one or the other of the cut-out mechanisms NTR—NS or RTR—RS.

The control relay Z is controlled from a local dispatcher's office DO containing the control apparatus for numerous switch machines, of which the lever L only has been illustrated, and in which office the indicating relay IR controls the indicating lamp IL. This indicating lamp IL is used to distinctively indicate the condition of the distant switch machine SM and the condition of occupancy of the detector track circuit containing detector track relay DT.

It is believed that the underlying features of the invention are most readily understood from a description of the operation of the apparatus illustrated.

Operation.—Under normal conditions of the apparatus as shown all of the various circuits are open and de-energized, except the detector track circuit which is a normally energized circuit and maintains the track relay DT in its energized condition. Let us assume that the operator or dispatcher in the tower DO desires to operate the track switch 6 to the take-siding position, and in order to do so moves the lever L to the left hand dotted position. In this position of the lever

L the following circuit for the control relay Z is completed:—beginning at the battery 10 contact of the lever L, winding of the indicating relay IR, line wire 12, front contact 13 of the detector track relay DT, wire 14, 5 winding of the control relay Z, wire 15, back contact 16 of the flashing relay FL to common return wire C connected to the other side of the battery thereof. With this circuit completed the control relay Z is energized to the left hand dotted position and then completes the following circuit for the left hand coil of the switch machine controller SMC, provided the detector track relay is 10 energized:—beginning at the terminal B, neutral contact 20 of the control relay Z, polar contact 21 in the left hand position, wires 22 and 23, winding 24 of the switch machine controller SMC, wires 25 and 26, front contact 27 of the track relay DT through 15 the common return wire C, back to the source of energy containing terminal B. Completion of this circuit causes the contact 28 of the switch machine controller to be moved to the left hand dotted position, in which it will remain until the opposite coil 29 of 20 this controller SMC is energized. In this connection it may be pointed out that in practice the front contact of a suitable approach locking relay is preferably contained 25 in the wire 26, so that this switch machine controller cannot be operated so long as the approach locking relay is de-energized, an arrangement of this kind is shown in the 30 Wight application above mentioned and may be used, if desired.

With the contact 28 of the toggle type switch machine controller SMC in its left hand dotted position the following circuit for 35 the switch machine SM is completed:—starting at the terminal B of the switch machine battery, contact 28 of the controller SMC, wire 30, thermal heating coil 31 of the thermal relay NTR, wire 32, back contact 40 33 of the stick relay NS, reverse circuit R of the switch machine SM, to the other terminal C of the local switch machine battery.

The completion of the circuit just traced causes the switch machine to operate the 45 switch 6 to the reverse or take-siding position. It should be noted that the switch box contacts 35 are bridged by the moving contact 36 in the switch box SB so long as the track switch 6 assumes an intermediate position. The bridging of these contacts, however, does not effect energization of the stick 55 relay NR or RS unless the corresponding thermal relays NTR or RTR have been operated. This feature of the system is to be 60 more clearly described hereinafter.

With the lever L in the left hand position and the control relay Z energized to the dotted position as heretofore explained, the indicating relay IR is also in its energized condition and the lamp IL in the dispatcher's 65

office DO is extinguished. Should now a train tread upon the detector track circuit containing track relay DT the contact 13 of this track relay is opened and the energizing circuit for the control relay Z and indicating relay IR is broken, so that the back contact 40 of the indicating relay IR closes the circuit for the indicating lamp IL. This circuit is so readily traced in the drawing that it need not be specifically considered. Should the switch machine, which is now energized until it has completed the operating stroke of the switch 6, not properly operate and allow the normal or reverse circuits N or R to remain closed too long, the overload relays NTR or RTR will be operated to close contacts 41—42, 43—44. In this connection it may be pointed out that the current carrying contact 41 is constructed of bimetallic thermal metal and is bent toward the left as the coil 31 is heated and eventually engages the contact 42, and in the same way a similar current-carrying contact 43 is constructed of thermal metal and is bent toward the right as the winding thereof is heated, and engages contact 44 when it has been heated to a predetermined extent.

Let us now assume that the reverse circuit for the switch machine SM heretofore traced is closed and that the coil 31 is heated to an extent to cause contact 41 to engage 42, possibly by reason of the fact that the switch machine SM was stalled by a lump of coal or ice, or the like. With the contacts 41—42 closed the following pick-up circuit for the stick relay NS is completed:—starting at the terminal B of the switch machine battery, contact 28 of controller SMC in the dotted position, wire 30, heating coil 31, contacts 41—42, wires 45 and 46, winding of the stick relay NS, wires 47 and 48, contacts 35—36 of the switch box SB, wire 49, to the normal return wire C connected to the opposite end.

With the pick up circuit just traced closed the stick relay NS is caused to assume its energized condition, and will thereafter be maintained energized through the following stick circuit:—beginning at the terminal B, contact 28 of the switch machine controller SMC, wire 30, coil 31 of thermal relay NTR, wire 32, contact 33 in its raised position, wires 50 and 46, winding of the relay NS, wires 47 and 48, contact 35—36, wire 49, to the other terminal C of the switch machine battery. With the stick relay NS in its energized condition the reverse circuit R for the switch machine SM is broken, so as to prevent injury to this switch machine by further flow of current through its apparatus; and further the contact 52 of the relay NS is closed.

Closure of the contact 52 of stick relay NS completes the following energizing circuit for the flashing relay FL:—beginning at the terminal B of a suitable battery, contact 20

of relay Z, polar contact 21 in the left hand dotted position, wires 22 and 53, front contact 52 of the stick relay NS, wires 54 and 55, winding of the flashing relay FL to common return wire C connected to the other terminal of said battery. With the flashing relay energized, as just explained, the contact 16 is attracted and the energizing circuit for the control Z is broken at this contact. The interruption of the energizing circuit for control relay Z also de-energizes the indicating relay IR connected in series therewith, so that the contact 40 of this relay IR is dropped and the indicating lamp IL in the dispatcher's office DO is illuminated. A short period of time after breaking of the circuit for control relay Z this control relay Z assumes its de-energized condition, opening its contact 20 and thereby breaking the energizing circuit for the flashing relay FL. After another short interval of time the flashing relay will again assume its de-energized condition, thereby completing the circuit for the control relay Z at the back contact 16 of this flashing relay FL, thus causing energization of the relays Z and IR and causing the indicating lamp IL to again be extinguished. It is, of course, understood that this illumination and extinction of the indicating lamp IL is repeated, so that this lamp IL is in fact continuously blinked or flashed, informing the operator that the switch machine has not completed its stroke, and its control circuit has been broken by one of the cut-out devices NTR-NS or RTR-RS. In this connection it may be pointed out that should a cut-out device be operated at the extreme end of the operating stroke on the switch machine, the contact 35-36 in the switch box would be open, and continual flashing of the indicating lamp IL will not result. If the operator is informed in a manner as just explained, that is by flashing of lamp IL, that the switch machine has been stalled by reason of an excessive current, or a normal current flowing for an excessive period, he may operate his lever L to the opposite position and in so doing interrupt the stick circuit for the particular stick relays NS or RS then energized, thereby returning the apparatus to normal, so that he may again energize the switch machine and operate it either toward the normal or toward the reverse position. In other words, the system illustrated not only shows circuit protecting apparatus for protecting the switch machine circuits against overload, or energization for an undue period of time, but also discloses means for restoring such cut-out apparatus to its normal in-active condition.

Attention is again directed to the fact, that the indicating lamp IL is not only useful to indicate by flashing thereof that the switch machine cut-out apparatus has functioned, but is also useful to indicate occupancy of the

detector track circuit containing track relay DT. It should be noted that with the control relay Z energized through the line circuit including line wire 12 and common return wire C, this energized condition of this line circuit also holds the indicating relay IR up, but that the treading of a train on the detector track circuit drops relay DT and in turn drops the indicating relay IR, and causes the indicating lamp IL to give a continuing non-flashing illumination so long as this detector track circuit remains occupied. 70 75

Having thus shown and described one rather specific embodiment of the invention, and having shown many of the devices of the system conventionally, it is desired to be understood that the particular apparatus illustrated has been selected to facilitate describing the underlying principles of the invention and not with any intent of limiting its scope 80 85 nor with the intent of illustrating the exact circuit arrangement preferably employed in carrying out the invention, and that various changes, modifications, and additions may be made to adapt the invention to the particular railway problem which the invention is called upon to solve, all without departing from the spirit of the invention or the idea of means underlying the same, except as demanded by the scope of the following claims. 90 95

What I claim is:—

1. In a system of control for switch machines, the combination with a distant switch machine, a polar control relay for controlling the operation of said switch machine, a local lever for controlling said polar relay through a simple line circuit, an indicating relay in said circuit near said lever, a cut-out device for cutting current off of said switch machine if such current is excessive, and means for intermittently opening said line circuit and intermittently actuating said indicating relay when current has been cut off of said switch machine by said cut-out device. 100 105

2. In a system of control for switch machines, the combination with a distant switch machine, a polar control relay for controlling the operation of said switch machine, a local lever for controlling said polar relay through the medium of a simple line circuit, an indicating relay in said circuit near said lever, a cut-out device for cutting current off of said switch machine if such current is excessive, means for intermittently opening said line circuit and intermittently actuating said indicating relay when current has been cut off of said switch machine, and means controlled by said lever and through the medium of said line wire for restoring said cut-out device to normal. 115 120 125

3. In a system of control for switch machines, the combination with a distant switch machine, a polar control relay for controlling the operation of said switch machine, a local 130

lever for controlling said polar relay through the medium of a simple line circuit, an indicating relay in said circuit near said lever, a cut-out device for cutting current off of said switch machine if such current is excessive, 5 means for intermittently actuating said indicating relay when current has been cut off of said switch machine by said cut-out device, and means controlled by said lever for restoring said cut-out device to normal.

10 4. In a system of control for switch machines, the combination with a distant switch machine, a polar control relay for controlling the operation of said switch machine, a local lever for controlling said polar relay through a simple line circuit, an indicating relay in 15 said circuit near said lever, a cut-out device for cutting current off of said switch machine if such current is excessive, a detector track circuit associated with the track switch operated by said switch machine, and means for intermittently opening said line circuit and intermittently actuating said indicating relay when said cut-out device is operated and 20 for opening said line circuit so long as said detector track circuit is occupied and giving a continuous indication during the passage of a train over said detector track circuit.

25 5. In a system of control for switch machines, the combination with a distant switch machine, a polar control relay for controlling the operation of said switch machine, a local lever for controlling said polar relay through a simple line circuit, an indicating relay in 30 said circuit near said lever, a cut-out device for cutting current off of said switch machine if such current is excessive, and means controlled by said switch machine for restoring said cut-out device to normal if it 35 has been operated near the end of the operating stroke and the switch machine has actually completed its operating stroke.

40 6. In a system of control for switch machines, the combination with a distant track switch, a switch machine for operating said track switch, said switch machine having a normal circuit for operating it to the normal position and a reverse circuit for operating it to the take-siding position, a polar relay 45 controlled from a local office over a line wire which if energized in one direction applies potential to the normal circuit and if energized in the other direction applies potential to the reverse circuit, a cut-out device in each 50 of said normal and reverse circuits each of which opens its associated circuit when the current flow therein is abnormal, and means effective if said polar relay is energized to apply potential to one of said switch machine 55 circuits for restoring to normal the cut-out device of the other switch machine circuit.

60 7. In a system of control for switch machines, the combination with a distant track switch, a switch machine for operating said track switch, said switch machine having a

normal circuit for operating it to the normal position and a reverse circuit for operating it to the take-siding position, a polar relay controlled from a local office over a line wire which if energized in one direction applies potential to the normal circuit and if energized in the other direction applies potential to the reverse circuit, a cut-out device in each of said normal and reverse circuits each of which opens its associated circuit when the current flow therein is abnormal, means effective if said polar relay is energized to apply potential to one of said switch machine circuits for restoring to normal the cut-out device of the other switch machine circuit, and means for indicating at the tower when one of said cut-out devices is in its actuated position.

75 8. In a system of control for switch machines, the combination with a distant track switch, a switch machine for operating said track switch, said switch machine having a normal circuit for operating it to the normal position and a reverse circuit for operating it to the take-siding position, a polar relay 80 controlled from a local office over a line wire which if energized in one direction applies potential to the normal circuit and if energized in the other direction applies potential to the reverse circuit, a cut-out device in each of said normal and reverse circuits each of which opens its associated circuit when the current flow therein is abnormal, and means actuated by the switch machine for restoring a cut-out device to normal if the switch machine is caused to assume an extreme normal or reverse position.

90 9. In a system of control for switch machines, the combination with a distant track switch, a switch machine for operating said track switch, said switch machine having a normal circuit for operating it to the normal position and a reverse circuit for operating it to the take-siding position, a polar relay 95 controlled from a local office over a line wire which if energized in one direction applies potential to the normal circuit and if energized in the other direction applies potential to the reverse circuit, a cut-out device in each of said normal and reverse circuits each of which opens its associated circuit when the current flow therein is abnormal, a detector track circuit associated with said track switch, and means for indicating at said office and through the medium of said line wire 100 the presence of a train on said detector track circuit.

115 10. In a system of control for switch machines, the combination with a distant track switch, a switch machine for operating said track switch, said switch machine having a normal circuit for operating it to the normal position and a reverse circuit for operating it to the take-siding position, a polar relay 120 controlled from a local office over a line wire 125

which if energized in one direction applies potential to the normal circuit and if energized in the other direction applies potential to the reverse circuit, a detector track circuit, 5 a cut-out device in each of said normal and reverse circuits each of which opens its associated circuit when the current flow therein is abnormal, means effective if said polar relay is energized to apply potential to one of said switch machine circuits for restoring 10 to normal the cut-out device of the other switch machine circuit, means for indicating at said office when one of said cut-out devices is in its actuated position, and means for indicating at said office and through the medium of said line wire the presence of a train 15 on said detector track circuit.

11. In a system of control for switch machines, the combination with a distant track switch, a switch machine for operating said track switch, said switch machine having a normal circuit for operating it to the normal position and a reverse circuit for operating it to the take-siding position, a polar relay 20 controlled from a local office over a line wire which if energized in one direction applies potential to the normal circuit and if energized in the other direction applies potential to the reverse circuit; a cut-out device in each 25 of said normal and reverse circuits each of which opens its associated circuit when the current flow therein is abnormal, which comprises a back contact of a stick relay which if open breaks the switch machine circuit, 30 a current responsive device which in response to excessive current in said circuit closes a pick-up circuit for said stick relay, and a stick circuit for said stick relay energized by current applied through the medium of 35 said polar relay; and means for causing said indicating relay to indicate when one of said cut-out devices assumes its actuated condition.

12. In a control system, the combination 40 with a motor located at a distant point, a source of current at said motor, a relay for controlling the operating circuit of said motor and applying current from said source to said motor when said relay is energized; 45 means for controlling said relay from a local point, a time-delayed cut-out device for said motor for opening the circuit of said motor upon the flow of an abnormal current therein, and means controlled by said motor for 50 restoring said cut-out device to normal.

13. In a control system, the combination 55 with a motor located at a distant point, a source of current at said motor, a relay for controlling the operating circuit of said motor and applying current from said source to said motor when said relay is energized, a line circuit for controlling said relay from a local point, a cut-out device for said motor for opening the circuit of said motor upon 60 the flow of an abnormal current therein,

means for restoring said cut-out device through the medium of said line circuit, and means for indicating at said local point and through the medium of the circuit for controlling said relay the operated condition of 65 said cut-out device.

14. In a system of control for switch machines, the combination with a distant switch machine, a control relay for controlling the operation of said switch machine, a local lever for controlling said control relay through a simple line circuit, an indicating relay in said circuit near said lever, a cut-out device for cutting current off of said switch machine if such current is excessive, and means for intermittently opening said line circuit and intermittently actuating said indicating relay when current has been cut off of said switch machine by said cut-out device.

15. In a system of control for switch machines, the combination with a distant switch machine, a control relay for controlling the operation of said switch machine, a local lever for controlling said control relay through the medium of a simple line circuit, 70 an indicating relay in said circuit near said lever, a cut-out device for cutting current off of said switch machine if such current is excessive, means for intermittently opening said line circuit and intermittently actuating said indicating relay when current has been cut off of said switch machine, and means controlled by said lever and through the medium of said line wire for restoring said cut-out device to normal.

16. In a system of control for switch machines, the combination with a distant switch machine, a control relay for controlling the operation of said switch machine, a local lever for controlling said control relay through the medium of a simple line circuit, 75 an indicating relay in said circuit near said lever, a cut-out device for cutting current off of said switch machine if such current is excessive, means for intermittently actuating said indicating relay when current has been cut off of said switch machine by said cut-out device, and means controlled by said lever for 80 restoring said cut-out device to normal.

17. In a system of control for switch machines, the combination with a distant switch machine, a control relay for controlling the operation of said switch machine, a local lever for controlling said control relay through a simple line circuit, an indicating 85 relay in said circuit near said lever, a cut-out device for cutting current off of said switch machine if such current is excessive, a detector track circuit associated with the track

switch operated by said switch machine, and means for intermittently opening said line circuit and intermittently actuating said indicating relay when said cut-out device is operated and for opening said line circuit so long as said detector track circuit is occupied 90

and giving a continuous indication during the passage of a train over said detector track circuit.

18. In a system of control for switch machines, the combination with a distant switch machine, a control relay for controlling the operation of said switch machine, a local lever for controlling said control relay through a simple line circuit, an indicating relay in said circuit near said lever, a cut-out device for cutting current off of said switch machine if such current is excessive, and means controlled by said switch machine for restoring said cut-out device to normal if it has been operated near the end of the operating stroke and the switch machine has actually completed its operating stroke.

19. In a system of control for switch machines, the combination with a distant track switch, a switch machine for operating said track switch, said switch machine having a normal circuit for operating it to the normal position and a reverse circuit for operating it to the take-siding position, a control relay controlled from a local office over a line wire which if energized by current of one character applies potential to the normal circuit and if energized by current of another character applies potential to the reverse circuit, a cut-out device in each of said normal and reverse circuits each of which opens its associated circuit when the current flow therein is abnormal, and means effective if said relay is energized to apply potential to one of said switch machine circuits for restoring to normal the cut-out device of the other switch machine circuit.

In testimony whereof I affix my signature.
